UNITED STATES PATENT OFFICE.

WILLIAM F. KIESEL, JR., OF ALTOONA, PENNSYLVANIA.

LOCOMOTIVE.

Application filed February 2, 1920. Serial No. 355,707.

To all whom it may concern:

Be it known that I, WILLIAM F. KIESEL, Jr., a citizen of the United States, and resident of Altoona, county of Blair, State of Pennsylvania, have invented certain new and useful Improvements in Locomotives, of which the following is a specification.

The present invention relates to locomotives and more particularly to the arrangement and disposition of the steam piping for supplying steam to the auxiliaries and steam operated apparatus at the front of the locomotive. Heretofore this apparatus has been supplied with steam by means of pipes disposed on the outside of the locomotive shell where they are subject to considerable condensation. Furthermore in most cases these pipes extended into the cab adding to the general congestion therein.

20 The principal objects of the present invention are to eliminate some of the piping on the outside of the locomotive extending from the cab to the front of the locomotive; to relieve the congestion of pipes and valves 25 in the cab; to locate the piping for supplying steam to the auxiliaries at the front of the boiler, within the shell, that is within the boiler and smoke box as far as possible; to provide a front bridge pipe having a valve 30 disposed within the shell and operable from the exterior thereof and to utilize this valve as a substitute for a gusset plate brace.

To the above ends the invention comprises a steam pipe, or front bridge pipe, extending 35 from the steam dome or other source of steam supply through the front head of the boiler into the smoke box, thence through the front head of the smoke box and thereafter branched to supply steam to the turbine, compressors and other apparatus. In 40 the smoke box the steam pipe is tapped to supply steam to the blower nozzles and smoke lifter. Within the boiler the bridge pipe has a valve for controlling the flow of 45 steam therein, said valve being operable from the outside of the boiler shell.

Other objects and features of novelty will be apparent from the description taken in connection with the drawings, in which— 50 Figure 1 is a side elevation at the front of a locomotive, parts being in section, illustrating the piping and valves arranged according to the present invention;

Figure 2 is a plan view of parts shown in 55 Fig. 1, portion of the smoke box shell being broken away;

Figure 3 is a front elevation of a locomotive equipped with the present invention, and

Figure 4 is a longitudinal sectional elevation through the valve in the bridge pipe and the adjacent shell.

Referring to the drawings, according to the present invention, steam for the apparatus at the front of the locomotive is taken 65 through a front bridge pipe 10 extending from the steam dome or other source of steam supply to the valve 11 disposed within the boiler shell adjacent the front flue sheet thereof, the pipe 10 also lying within the 70 boiler shell. From the valve 11 a pipe 12 extends to a T 13. From this T a pipe 14 extends through the front head 15 of the smoke box where it is provided with a branch pipe 16 for supplying steam to the 75 head light turbine and with a lubricator 17. Thereafter the pipe is branched, one branch 18 supplying steam to the compound air compressor 19 and the other branch 20 supplying steam to a like compound air compressor 21 at the opposite side of the locomotive. The exhaust from the compressor 19 is conducted through a pipe 22, to the blower nozzle casting 23; this casting having a plurality of blower nozzles 24, each of 80 which discharges into one of a plurality of vertical passages 35 in the stack. The opposite compressor 21 has an exhaust pipe 26 which extends to the opposite end of the nozzle casting 23. *90

The T 13 within the smoke box of the locomotive has a pipe 27 leading to a valve 28 which controls the supply of steam through pipe 29 to the nozzle casting 23. Above the valve 28 the pipe 27 is tapped to supply 95 steam through a pipe 30 to a smoke lifter valve 31 which controls the supply of steam through a pipe 32 to a smoke lifter at the top of the stack.

The valve 11 which controls the supply 100 of steam to the steam consuming apparatus at the front of the locomotive preferably comprises an elongated body 33 having an inlet chamber 34 separated by a ported wall 35 from the outlet chamber 36. In addition 105 to the usual inlet opening for the inlet chamber 34 the valve body is also provided with an opening for the removable bonnet 37, a flange 38 being provided around this opening. According to the present invention this flange is secured to the boiler shell 39 by rivets 40. Further if desired a leak tight

connection may be provided by a weld such as indicated at 41. The bonnet 37 extends through an opening 42 in the boiler shell which registers with the adjacent opening in the body 33 of the valve. This bonnet is secured in position in any suitable manner as by means of the studs 43. A valve stem 44 extends through the bonnet and is carried thereby, and at its inner end has a projection and slot connection with a valve disk 45 which controls the ports in the wall 35. A suitable stuffing box 46 may be provided around the stem 44. It will be observed that the bonnet 37 together with the valve stem 10 may be removed from the valve from the exterior of the boiler, thus giving access to the interior of the valve. At its outlet end the valve extends through the front flue sheet 47 of the boiler and is rigidly connected 15 thereto. For this purpose, as shown, the valve body has a flange 48 bearing against the interior surface of the flue sheet and a nut 49 screwed on the outlet end of the valve body on the other side of the flue sheet adapted 20 to clamp the flue sheet against the shoulder when it is screwed up. In this manner, as the valve body is secured to the boiler shell and flue sheet, it acts as a gusset plate 25 to hold the flue sheet against deflection.

30 It will be observed, according to the present invention, except for the very short length in front of the locomotive head, all the piping for supplying the auxiliaries is disposed within the boiler shell and hence 35 there is practically no condensation of steam therein. Furthermore, the valves and piping heretofore extending to the cab have been eliminated, and yet the supply of steam may be readily controlled because of the valve 11 40 operable from the outside of the boiler shell.

Although a specific arrangement of the piping and a specific valve for controlling the same have been described in detail, it is to be understood that the invention is not 45 thus limited, but includes modifications and changes which come within the scope of the appended claims.

Having thus described my invention what I claim as new and desire to secure by Letters Patent is:

- 50 1. In a locomotive having a smoke box at the front thereof and steam operated auxiliary apparatus in front of said box, the improved means for supplying steam to said apparatus comprising a front bridge pipe extending through the front flue-sheet of the boiler and the smoke box to said apparatus and means to control the supply of steam to said apparatus.
- 60 2. In a locomotive having steam operated auxiliary apparatus at the front thereof, the improved means for supplying steam to said apparatus comprising a front bridge pipe extending through the front flue sheet 65 of the boiler the smoke box and the front

head and a valve in said pipe to control the flow of steam therein.

3. In a locomotive having a smoke box at the front thereof and steam operated auxiliary apparatus in front of said box, the improved means for supplying steam to said apparatus comprising a front bridge pipe extending through the front flue-sheet of the boiler and the smoke box to said apparatus and a valve in said pipe operable from the exterior of the boiler to control the flow of steam therein. 75

4. In a locomotive having a smoke box at the front thereof and steam operated auxiliary apparatus in front of said box, the improved means for supplying steam to said apparatus comprising a front bridge pipe having a valve therein within the boiler shell operable from the exterior thereof. 80

5. In a locomotive having steam operated apparatus at the front thereof, the improved means for supplying steam to said apparatus comprising a front bridge pipe having a valve secured on the interior of the boiler shell provided with an operating member extending through the shell and operable from the exterior thereof. 90

6. In a locomotive having steam operated apparatus at the front thereof, the improved means for supplying steam to said apparatus comprising a front bridge pipe, a valve in said pipe secured to the boiler shell on the interior thereof, said valve having a bonnet extending through an aperture in the shell into the body, means on the exterior of the shell to removably secure said bonnet in said body, and the valve stem extending through the bonnet into the valve whereby it may be operated from the exterior of the shell. 100

7. In a locomotive having steam operated apparatus at the front thereof, the improved means for supplying steam to said apparatus comprising a valve within the boiler shell having an operating member on the exterior thereof and a part extending through, and secured to, the front flue sheet, a steam pipe extending to said valve and a pipe for supplying said apparatus connected to said part in front of said sheet. 110

8. In a locomotive having steam operated apparatus at the front thereof, the improved means for supplying steam to said apparatus including a valve within the boiler secured to the boiler shell and front flue sheet to act as a gusset plate, said valve having an operating member on the exterior of the shell, a steam supply pipe extending to said valve and a pipe extending from the valve to said apparatus. 120

9. In a locomotive having steam operated apparatus at the front thereof, the improved means for supplying steam to said apparatus including a valve within the boiler secured to the boiler shell and front 130

flue sheet to act as a gusset plate, a steam supply pipe extending to said valve and a pipe extending from said valve to said apparatus.

5 10. In a locomotive having steam operated apparatus at the front thereof, the improved means for supplying steam to said apparatus including a steam pipe extending within the boiler through the front flue sheet, the smoke box and front head to the apparatus in front of said head.

10 15. In a locomotive having steam operated apparatus at the front thereof, the improved means for supplying steam to said apparatus including a steam pipe extending within the boiler through the front flue sheet, the smoke box and front head to the apparatus in front of said head and a branch pipe wholly within the smoke box 20 extending from said steam pipe to the blower nozzle under the stack.

12. In a locomotive having steam operated apparatus at the front thereof, the improved means for supplying steam to said

apparatus including a steam pipe extending within the boiler through the front flue sheet, the smoke box and front head to the apparatus in front of said head and a branch pipe connected to said steam pipe in the smoke box to furnish smoke lifter 30 steam at the upper peripheral edge of the stack.

13. In a locomotive in combination, a valve body having an inlet, an outlet, and an opening for the bonnet, means securing 35 said body to the boiler shell adjacent the front flue sheet with said opening in register with an aperture in the shell, means also securing the body to the front flue sheet with a portion projecting therethrough, a removable bonnet in said body opening, means accessible from the outside of the shell securing said bonnet in said opening and a valve operating member carried by said bonnet. 40 45

In testimony whereof I affix my signature.

WILLIAM F. KIESEL, JR.
